CLAIM

The ornamental design for a rear combination lamp for automobile as shown and described.

DESCRIPTION

FIG. 1 is a front and top perspective view of a rear combination lamp for automobile showing my new design; FIG. 2 is a front and bottom perspective view thereof; FIG. 3 is a front elevation view thereof; FIG. 4 is a rear elevation view thereof; FIG. 5 is a top plan view thereof; FIG. 6 is a bottom plan view thereof.

FIG. 7 is a left side elevation view thereof; and, FIG. 8 is a right side elevation view thereof.

The claimed design is indicated by the relatively dark portions in the figures, while the relatively light and de-emphasized portions form no part of the claimed design.

1 Claim, 8 Drawing Sheets
